UNITED STATES PATENT OFFICE.

WALTER SCOTT WILLIAMS, OF CLINTON, ILLINOIS, ASSIGNOR OF TWENTY-EIGHT ONE-HUNDREDTHS TO CHARLES W. PIFER, TWENTY-EIGHT ONE-HUNDREDTHS TO CHARLES R. WESCOTT, AND FIFTEEN ONE-HUNDREDTHS TO WILLIAM H. H. HASTINGS, OF CLINTON, ILLINOIS.

GRAIN-DOOR FOR CARS.

No. 927,700.

Specification of Letters Patent.

Patented July 13, 1909.

Application filed May 25, 1908. Serial No. 434,952.

To all whom it may concern:

Be it known that I, WALTER SCOTT WILLIAMS, a citizen of the United States, residing at Clinton, in the county of DeWitt and 5 State of Illinois, have invented certain new and useful Improvements in Grain-Doors for Cars, of which the following is a specification.

My invention relates to the improvement 10 of grain doors for cars and the objects of my invention are to provide an improved construction of doors adapted for use in connection with cars carrying grain or other commodities; to so construct my improved 15 doors as to admit of their being readily opened when they are subjected to the pressure of grain within the car; to provide improved means for locking the doors and for preventing the escape of grain beneath or 20 about the same; to provide in conjunction therewith improved means for closing the upper portion of the car doorway and to so construct metallic or wooden doors for grain cars as to permit of their being easily and 25 readily handled. These objects I accomplish in the manner illustrated in the accompanying drawing, in which:

Figure 1 is a face view of a car body showing my improved doors therein in a 30 closed position, Fig. 2 is an enlarged section on line $x-x$ of Fig. 1, Fig. 3 is an enlarged section on line $y-y$ of Fig. 1, Fig. 4 is an enlarged transverse section on line $z-z$ of Fig. 1, Fig. 5 is an enlarged detail view in 35 elevation illustrating the manner of hinging the inner door sections, and, Fig. 6 is a view of the base of one of said hinges taken at right angles with that shown in Fig. 4.

Similar numerals refer to similar parts 40 throughout the several views.

1 represents a car body and 2 one of the doorways thereof.

3 represents a fixed door sill plate which is secured to the floor of a car and extends before 45 tween the sides of the doorway in the inner portion thereof. To the outer edge of the plate 3 is hinged a second sill plate member 4, the latter when extended outward, lying in a recess 5 of the door entrance and terminating in a downturned flange 6 which engages an outer and second recess 7 which is formed in the outer face and upper portion of the wood sill of the doorway. It will thus be observed that the plates 2 and 4 form a

complete metal covering for the sill or entrance to the door. 55

Within the car and at each side of the doorway, I provide a fixed vertical hinge rod 8 each of the latter having formed on its lower end an enlarged collar or boss 9, the upper side of which is provided in its rear portion with a notch or recess 10. Mounted to swing upon each of the rods 8 is a vertically disposed metallic door section 11 which is preferably of metal and to the outer vertical edges of these door sections are hinged as indicated at 12, outer door sections 13. Each of the sections 11 has its inner vertical edge portion shaped to form a substantially tube-like hinge sleeve 14 through 60 which the hinge rod 8 passes loosely. The lower end of each of these hinge sleeves is inclined as indicated at 14^a in Fig. 5, this inclined lower end being adapted to ride upon the upper side of the 65 corresponding boss collar 9. One of the door sections 13 has its outer edge portion provided with an outwardly projecting extension or lip 13^a which when the door sections are extended, overlaps the outer edge 70 of the opposite section 13. 75

Pivoted to the outer side and lower portion of each of the door sections 13 is one end of a depending latch plate 15, the lower end of the latter normally extending below 80 the lower end of the door section with which it is connected and adapted to engage the outer side of the vertical extension 6 of the sill plate member 4 when the latter is turned upward and inward against the door sections, as shown in Figs. 1 and 3 of the drawing. One of the door sections 13 has pivotally connected therewith one end of a latch bar 16, said latch bar being adapted to be 85 swung to the horizontal position shown in Fig. 1 of the drawing and to have its otherwise free end engage a suitable catch projection 17 on the outer face of the remaining door section 13. 90

As indicated in the drawing, the door sections 11 and 13 have their upper terminations at points below the top of the doorway or frame and in order that the space above said door sections may be closed if desired, I provide an upper door horizontal section 100 18 which has its upper edge portion suitably hinged on the inner side of the car above the doorway and which as indicated in Fig. 4 105

of the drawing, has its end portions provided with transverse rounded extensions which are adapted to engage or embrace the upper portions of the rods 8 when said door 5 is in the lowered position shown in full lines in Figs. 1 and 3. On its outer face the door section 18 is provided with a depending pivoted latch plate 19, the lower end of which is adapted to depend in front of and 10 engage the upper ends of the door sections 13. The section 18, however, may as indicated in dotted lines in Fig. 3 of the drawing, be swung upwardly and inwardly, its outer edge portion being adapted to engage 15 a suitable angular catch hanger 20 which depends from the underside of the car roof frame.

When a car equipped with my improved grain doors is to be unloaded, it will be 20 understood that the sill plate member 4 is first disengaged from the latch plates 15 by turning the latter upward, after which said plate member is turned downward and forward to the position indicated in dotted 25 lines in Fig. 3 of the drawing. The upper door section having been swung to and secured in the raised position shown in dotted lines in Fig. 3, the latch bar 16 is disengaged from the catch 17 permitting the door sections 30 11 and 13 to be swung outward.

While it is obvious that each pair of door sections 11 and 13 may be formed as a single or integral door, it will readily be understood that such construction would necessitate the projection of the doors when in 35 their open positions to an undesirable distance from the car doorway and that the employment of two door sections on each side of the center of the doorway, which 40 sections are hinged one to the other, permits of the sections 13 being folded backward toward the car when the doors are open in such position as not to interfere with or engage objects on the outer side of 45 the car.

In order that the doors when in their open positions may be latched against voluntary closing, I have provided the recesses or notches 10 in the collars 9 and the inclined 50 lower ends 14^a on the door hinge sleeves 14, the notches of the collars 9 being so located

as to permit of the lower ends of said hinge sleeves dropping into engagement therewith when the doors are thrown to the open position and thereby necessitating a slight 55 raising of the doors preparatory to closing the same. From the construction and operation described, it will be seen that a simple, reliable and effective sectional closure is provided for car doorways, the sections thereof 60 being so hinged and constructed as to permit of the same being formed of metal and at the same time preventing them from being unwieldy or difficult to handle on account of their weight and rigidity. 65

What I claim is:

In a grain door car construction, the combination with a car, having a doorway therein, of a vertical hinge rod located at each side of said doorway, a horizontally swinging door hinged upon each of said rods, each of said doors comprising two sections hingedly connected to each other, a vertically swinging door hingedly connected to the top of the doorway, the lower edge of which 75 lies inside of said horizontally swinging doors when said vertically swinging door is lowered, a latch carried by said vertically swinging door and adapted to engage the upper edge of the horizontally swinging 80 doors at their juncture, means for latching said horizontally swinging doors, a fixed metallic sill plate member mounted upon the sill of the doorway, a hinged sill plate member hingedly connected thereto, and 85 comprising a body portion 4 and a flange 6, the hinged connection between the hinged and fixed sill plate members lying inside of the outer edge of the door sill, said door sill being cut away to receive the flange 6 when 90 the hinged sill plate member is thrown outwardly and downwardly, and latches carried by the horizontally swinging doors and having offset portions adapted to engage over the flange 6 when the hinged sill plate member is thrown inwardly and upwardly. 95

In testimony whereof I affix my signature in presence of two witnesses,

WALTER SCOTT WILLIAMS.

Witnesses:

CHARLES W. PIFER,

CHARLES R. WESCOTT.
